UNITED STATES PATENT OFFICE.

JOHN O. WINKS, OF SAN FRANCISCO, CALIFORNIA.

ROTARY MOTOR.

1,270,909.

Specification of Letters Patent.

Patented July 2, 1918.

Application filed March 20, 1917. Serial No. 156,162.

To all whom it may concern:

Be it known that I, JOHN O. WINKS, a citizen of the United States, and a resident of the city and county of San Francisco, State 5 of California, have made a new and useful invention—to-wit, Improvement in Rotary Motors; and I do hereby declare the following to be a full, clear, concise, and exact description of the same.

10 The invention relates particularly to rotary motors of the internal combustion type, having reciprocating pistons therein. One object of the invention is to provide a motor of this type, simple in construction, direct 15 in action and capable of using efficiently expansive force as a power.

Another object is to so assemble the working parts that leakage and friction are reduced to the minimum.

20 In the specification and the annexed drawings, I illustrate the invention in the form considered by me to be the best, but it is to be understood that the invention is not limited to such form because it may be embodied in other forms, and it is also to be understood that in and by the claims following the description, it is desired to cover the invention in whatever form it may be embodied.

30 In the accompanying one sheet of drawing,

Figure 1 is a side elevation of a motor constructed in accordance with this invention, in cross section on the line I—I, Fig. 2.

35 Fig. 2 is a side elevation of the same, a portion of the stator being removed in cross section to disclose the underlying mechanism and interrelation of parts.

Fig. 3 is a plan view from above in cross 40 section taken on the line III—III, Fig. 1.

Fig. 4 is a detail view in perspective of a piston.

Fig. 5 is a similar view of a cylinder sleeve having valve ports arranged therein.

45 Fig. 6 is a fragmentary sectional detail of the insulated commutator sector adapted to convey electrical ignition to the spark plug.

In detail the construction illustrated in the drawings includes the stator 1 having a 50 suitable base 2 cast thereon. The stator has an interior elliptical periphery, and for convenience in manufacture and accessibility is preferably divided horizontally and bolted together as indicated in Fig. 1. The sides 55 of the stator are suitably countersunk to re-

ceive the covers 3 and 4 bolted to the opposite faces thereof.

The rotor 5 is concentric with and fixed to the hollow shafts 6 and 7 projecting from the opposite sides on the axis of the rotor 60 and suitably journaled in the bearings 8 and 9, provided therefor in the covers 3 and 4. The exterior of the rotor is parallel with the surface of the interior periphery of the stator, with which it approximates contact 65 at the narrowest point of the stator, in the present instance on the horizontal diameter thereof, see Fig 1. The shafts 6 and 7 form an integral part of or are fixed in the side walls 10 and 11 respectively of the rotor. 70 The rotor is bored transversely on its diameter to receive the sleeve 12, slideable therein and operated and controlled by a stud 16 provided with an antifriction roller 14 engaging a cam slot 15 milled in the side of 75 the plate 4. The curve of the cam slot being plotted to time the reciprocations of the cylinder sleeve 12 to control the inlet and outlet ports for the various cycles synchronously with the operation of the pistons as 80 hereinafter more fully described. The pistons 16¹ and 17 reciprocate in the rotor in opposed relation within the cylinder sleeve 12, the pistons being provided with the overhanging annular heads 18 and 19, re- 85 spectively engaging annular recesses in the opposite ends of the cylinder sleeve, to limit the inward thrust of the pistons to maintain the fixed displacement of the combustion chamber 20, between the opposed inner ends 90 of the pistons. Combustible fuel is admitted into the combustion chamber through the bore 21 in the hollow shaft 7 communicating with the carburetor 22, suitably connected to the fuel supply, not shown. The bore 21 through the shaft 7 terminates in a port 23 95 registering with the port 24 controlled by the stud 16 and the cam slot 15, see Fig. 5, during the suction cycle of the piston which operates on the four cycle principle.

When the motor is turned by the self starter or by hand in initiating its operation, the centrifugal force throws the pistons outward from the center, increasing the volume of the combustion chamber limited 105 and controlled by the ellipse of the periphery of the stator, the separation of the pistons creating a suction therebetween in the combustion chamber 20, the cylinder sleeve 12 being synchronously operated bringing the 110

ports 23 and 24 into register. The suction between the pistons operates upon the carburetor to suck in the carbureted mixture of air and fuel. The suction cycle reaching 5 its maximum when the pistons are in the vertical position 90° from the position illustrated in Fig. 1, which is the maximum of the suction cycle. Continued rotation of the rotor causes the contour of the stator to 10 force the pistons again together, compressing the fuel mixture contained within the combustion chamber between the inner ends of the pistons, until the pistons again reach the horizontal position as illustrated in Fig. 15 1, which is the maximum of the compression stroke. The ports 23 and 24 are forced out of registry by the cam 15 just as the maximum of the suction stroke is passed. At or near the maximum of the compression 20 cycle, electrical ignition energy is conducted through the cable 25 from a suitable source of supply, not shown, being grounded upon the stator as at 26, the opposite end leading to the commutator 27, the leads 28 conduct- 25 ing the current through the insulated terminal of the spark plug 29, causing a hot, igniting spark to jump across the terminals of the spark plug, exposed within the combustion chamber 20 through the port 30 30 formed in the sleeve 12. The spark ignites the compressed fuel within the combustion chamber, the combustion of the fuel expanding to force the pistons apart, this being the power stroke of the motor called the combustion cycle.

The outer end of the pistons bearing against the periphery of the stator cause a wedging or prying action, the leverage of which operates to rotate the rotor 5 until 35 the pistons have reached the limit of their outward throw which would be the vertical position (see Fig. 1), which is the maximum of the combustion cycle, during which the expanding gases have exerted their power. 40 At this point the port 31 in the sleeve 12 is brought into registry with the port 32 in the rotor by the operation of the cam 15, the port 31 opening into the central bore 33 in the shaft 6 permits the products of combustion 45 to exhaust thereinto during the next cycle which is called the exhaust cycle, represented by the travel of the pistons from the maximum combustion cycle to the minimum of the exhaust cycle, represented by 50 the pistons in Fig. 1, which are thereby restored to the position for initiating the suction cycle and the various cycles enumerated; consisting in drawing in a charge of fuel compressing it, firing it, exhausting or 55 scavenging out the products of combustion. During the combustion cycle or power stroke sufficient energy is stored in the fly wheel 34 fixed on the shaft 6, to carry the rotor through the succeeding cycles of suction, compression and exhaust.

The interior mechanism may be lubricated by introducing a suitable lubricant with the fuel through the shaft 7, the oil being drawn outward and distributed by the centrifugal force exerted by the rotor. 70

It is manifest that by a suitable arrangement of valves an expansive fluid, such as steam, compressed air, or the like, may be substituted for the combustible fuel, and introduced into the combustion chamber 20, 75 with obvious results, in which case the electrical ignition would be dispensed with.

The covers 3 and 4 are provided with lateral openings 34 through which air will be caused to circulate by the rotation of the rotor, such circulation tending to keep the rotor at normal temperature. 80

It is obvious that the motor is reversible, in that it will operate in either direction, according to which direction it is started in. 85

Having thus described my invention, what I claim and desire to secure by Letters Patent is:

1. A rotary motor including a stator formed with a deviating surface, a rotor journaled within said stator, a cylinder extending diametrically of said rotor, a reciprocal sleeve mounted within said cylinder, two pistons reciprocally mounted in the respective ends of said sleeve and bearing at 90 their outer ends upon said deviating surface, said cylinder being provided with an inlet and an exhaust port to align with an inlet and exhaust port in said sleeve arranged between the inner ends of said pistons, means for controlling said ports, consisting of a cam slot on said stator, and means on the sleeve engaging said cam for operating said port controlling means. 95

2. A rotary motor including a stator 105 formed with a deviating surface, a rotor journaled within said stator, a cylinder extending diametrically of said rotor, a reciprocal sleeve mounted within said cylinder, two pistons reciprocally mounted in the re- 110 spective ends of said sleeve, said cylinder being provided with an inlet and an outlet port, arranged between the inner ends of said piston, said sleeve being provided with ports, a cam on said stator, a roller on said 115 sleeve engaging said cam to reciprocate said sleeve to cause said sleeve to uncover and cover said inlet and outlet ports to operate the motor.

3. A rotary motor including a stator hav- 120 ing a deviating periphery; a transverse sleeve in said rotor having valve ports therein registering with ports in said rotor; pistons reciprocal in said sleeve and bearing against said deviating periphery; and means 125 for moving said sleeve synchronously with the movement of said pistons.

4. A rotary motor including a stator hav- 130 ing a deviating periphery; a rotor having ports therein; a transverse cylindrical sleeve

in said rotor having ports therein; pistons reciprocal in said sleeve and bearing against said deviating periphery; means for moving said sleeve synchronously with the reciprocations of said pistons.

5. A rotary motor including a stator formed with a deviating surface, a rotor journaled within said stator having an outside diameter approximating the narrowest 10 diameter of the stator, a cylinder extending diametrically of said rotor, a reciprocal sleeve within said cylinder, a pair of pistons reciprocally mounted respectively in the ends of the sleeve; inlet and outlet ports in said

sleeve, said cylinder being provided with an 15 inlet and an outlet arranged substantially opposite each other between the inner ends of said pistons positioned so as to align with the sleeve ports, and means for controlling said sleeve ports to operate the engine.

In testimony whereof, I have hereunto set my hand at San Francisco, California, this 28th day of February, 1917.

JOHN O. WINKS.

In presence of—
BALDWIN VALE,
A. J. HENRY.
